United States Patent Office.

BENJAMIN A. WARD, OF LYNN, MASSACHUSETTS.

Design No. 4,453, dated November 1, 1870.

DESIGN FOR A FRAME.

The Schedule referred to in these Letters Patent and making part of the same.

I, BENJAMIN A. WARD, of Lynn, county of Essex and State of Massachusetts, have invented and produced a new and original Design for a Frame, of which the following is a specification.

The nature of my design is fully represented in the accompanying photographic illustration, to which reference is made.

Above the center A are crossed keys B B, above which is a triple-crowned hat, C, surmounted by a globe, D, on the top of which is a cross, E.

On the right and left of center A are pillars F F, connected with the center by crosses G G, and surrounded by crosses H H.

Between the center A and crosses H H are scourges

I I, the one on the right crossed by sponge J, that on the left by spear K.

Between the cross H and key B on the right is a miter, L, while between the cross H and key B on the left is a staff, M.

Below the center A is a cross, N, on the right and left of which are books O O, surrounded by scroll-work.

I claim as my invention—

The design for a frame, substantially as shown.
BENJ. A. WARD.
